(57) **CLAIM**

The ornamental design for a tank actuation panel, as shown and described.

DESCRIPTION

FIG. 1 is a perspective view of the tank actuation panel embodying new design;

FIG. 2 is a top plan view thereof;

FIG. 3 is a front elevational view thereof;

FIG. 4 is a rear elevational view thereof;

FIG. 5 is a left side elevational thereof; and,

FIG. 6 is a right side elevational view thereof.

The broken line showing of the tank actuation panel is for the purpose of illustrating environmental structure and forms no part of the claimed design.
